UNITED STATES PATENT OFFICE

MARTIN L. DUNNAM, OF MERIDIAN, MISSISSIPPI.

COMBINED CONDENSER AND FEED-WATER HEATER.

1,076,410.

Specification of Letters Patent.

Patented Oct. 21. 1913.

Application filed September 30, 1912. Serial No. 723,220.

To all whom it may concern:

Be it known that I, MARTIN L. DUNNAM, a citizen of the United States, residing at Meridian, in the county of Lauderdale and State of Mississippi, have invented new and useful Improvements in Combined Condensers and Feed-Water Heaters, of which the following is a specification.

This invention relates to improvements in purifying boiler feed water, and more particularly to a combined condenser and feed water heater.

The object of this invention is to purify boiler water from solid and chemical impurities and afterward to retain the feed water in a preheated condition until delivered to the boiler.

While the preferred forms of this invention are illustrated upon the accompanying sheet of drawing, yet it is to be understood that minor detail changes may be made without departing from the scope thereof.

Figure 1 is a view in vertical longitudinal section, of the combined condenser and feed water heater as contemplated in this invention. Fig. 2 is an enlarged view in transverse vertical section of the condenser and feed water heater as contemplated in this invention.

The condenser and feed water heater comprises a cylindrical casing 1 closed at each end, supported above a horizontal heating chamber 2 extending the entire length thereunder and having a vertical flue or chimney 3 at one end to supply heat to vaporize the water in the condenser. Waste heat from the boilers may be employed to supply heat to the chamber 2 or a grate 4 may be provided at the end opposite the flue 3. It is preferable to provide an inner wall 5 about the upper portion of the casing 1 leaving a small space therebetween. The pipe 6 leading from a source of water supply discharges into the space at the bottom on one side and upon the other side an external feed pipe 7 leads from the bottom of this space into the interior of the casing 1 below the horizontal center line. The lower end of the feed pipe 7 is provided with a float operated valve 8 arranged to close the discharge end of the feed pipe. By this construction the water from the source of supply is raised in temperature before being led into the vaporizing portion of the condenser.

A plurality of horizontal air pipes 9 are arranged in the upper portion of the casing

1 in rows following the contour of the casing as near as possible. These pipes 9 are supported in the end walls of the casing and are open therethrough, so that cool air will be drawn through by the draft up the flue 3. Below each row of air pipes 9 are arranged correspondingly curved drip plates 10 supported from the end walls of the casing 1 to catch the drip of condensation which gathers upon the air pipes 9. Drip plates 10 have their lower side edges so constructed as to lead the drip into horizontal troughs 11 arranged diametrically opposite each other and secured to the sides of the casing 1. These troughs 11 are preferably curved on the radius of a circle having their outer sides tightly secured against the inner walls of the casing 1 and their inner sides extending slightly beyond a semicircle, so that the drip may be caught and retained by them. The float valve 8 is adjusted to retain the water level in the casing below the bottom of the drip trough 11. Through the front end of the casing 1 pipes 12 lead from the bottom of the drip trough and are connected to a pipe 13 leading to a pump, which forces the condensed water through a pipe to feed the boiler or batteries of boilers.

By means of this invention the water is preheated by passing over the upper walls of the condenser proper, vaporized in the bottom of the condenser proper, condensed in the upper part of the condenser proper and completely purified and held in troughs 11 as heated feed water until discharged through the boilers.

What I claim is:

1. A combined condenser and feed water heater, comprising a casing closed at each end, a heating chamber thereunder having a flue passing one end of the casing, a plurality of pipes in the casing leading from the air at one end to the flue at the other end, drip plates below the pipe, troughs at each side to catch the drip, means to admit the water to be vaporized, and means to lead the condensation in the troughs to the boilers.

2. A combined condenser and feed water heater, comprising a casing, air cooled pipes passing therethrough, double walls about the top of the casing forming a space therebetween, means to supply water to said space, and means to lead the water from this space to the bottom of the interior of the casing, means to vaporize the water in the bottom

- of the casing and preheat the water in the top space by the waste heat of vaporization, means for condensing the vapor in the casing, and means for retaining the condensation within the casing until fed to the boiler.
3. A combined condenser and feed water heater, comprising a casing closed at each end, a heating chamber thereunder, a plurality of parallel pipes arranged in curved rows passing through each end and communicating with the atmosphere, drip plates below each row of pipes, troughs at each side to catch the drip, means to admit water to be vaporized, and means to lead the condensation in the troughs to the
- 10 each end and communicating with the atmosphere, drip plates below the pipes, troughs at each side to catch the drip, means to admit water to be vaporized, means to lead the condensation in the troughs to the
- 15 boilers.

4. A combined condenser and feed water heater, comprising a casing closed at each end, a heating chamber thereunder, a plurality of parallel pipes arranged in curved rows passing through each end and communicating with the atmosphere, drip plates below each row of pipes, troughs at each side to catch the drip, means to admit water to be vaporized, and means to lead the condensation in the troughs to the boiler.

MARTIN L. DUNNAM.
